UNITED STATES PATENT OFFICE.

CLAUDE ALBERT CLAREMONT, OF ROSSLYN HILL, HAMPSTEAD, ENGLAND.

GAMES RACKET.

Application filed December 9, 1927, Serial No. 238,920, and in Great Britain September 25, 1926.

This invention relates to rackets for games such as tennis, badminton, etc. Rackets are usually made with a wooden rim and strung with gut, but rackets are also made with metal 5 rims, and also with strings made of metal wire.

The wire-stringing has certain advantages over gut-stringing such as durability, and constancy of tension notwithstanding atmospheric changes, but it loses the desired resiliency afforded by gut-stringing. Efforts have been made, by twisting, or in other ways manipulating wire, to attain such resiliency, but not with satisfactory results.

10 The object of this invention is to enable a racket to be made with stringing of metal wires, and attain the desired resiliency better than has heretofore been done, and a further object is to effect an improvement in 20 gut-strung rackets, or rackets strung in other ways.

Hitherto in all rackets heretofore made the desired resiliency has been sought to be obtained from the strings and the method of 25 stringing has been such as to inhibit distortion of the rim in the plane of the racket. This invention is based on a new principle and seeks to obtain the desired resiliency wholly or partly by means of distortion of 30 an elastic rim in the plane of the blade.

Hence the invention consists in the combination of a particular method of stringing hereinafter explained, and a rim pliable in the plane of the racket.

35 Accordingly in this invention the rim is made of any suitable material including steel and wood capable of yielding to the required extent under applied force, in the plane of the racket. In the case of stringing of steel 40 wires or other comparatively nonstretchable material and in a less degree in the case of gut stringing, to obtain resiliency reliance is placed on a distortion of the rim in the said plane against the reaction of its own 45 elasticity.

In the case of a stringing made of gut or other material affording resiliency, the resiliency rim apart from the purpose of affording resiliency is useful for the purpose of permanently maintaining the desired tension of 50 the gut.

The rim may be of various cross-section shapes consistent with obtaining the desired

resiliency and affording the required strength and weight.

55 It will be realized that to obtain resiliency from the pliability of the rim in the plane of the blade necessitates that the rim shall contract along one or more predetermined diameters and expand on one or more other diameters, and accordingly the stringing must be such that while admitting of the former movement it does not inhibit the latter movement.

60 It follows that it is an essential condition that the distance between the points of attachment of each string (except perhaps in some areas of the blade of the racket where it would be immaterial) shall not be increased by the predetermined permitted distortions of the 70 rim, as each string whose points of attachment violate this condition would inhibit the desired distortion.

65 Although it might be determined to so construct the stringing that the rim would contract on any one or more diameters, with consequential extensions in other directions, for the purpose of facilitating the elucidation of this invention, so far as concerns the 75 stringing, I propose to describe the method of stringing in reference to a quasi-elliptical blade, the longest diameter being in line with the handle, and on the basis that the resiliency is to be attained by a contraction of the longest diameter with consequential extension of the shortest diameter.

80 Of course, one set of strings more or less parallel to the longest diameter covering the whole area of the blade of the racket would 90 meet the required condition, but it is essential, in order to secure other required qualities of a racket, that one set of strings shall cross (and perhaps interlace with) another set, and if another set were arranged across and 95 normal to such a set as above described, the points of attachment of the second set would violate the condition.

100 It will be realized that, many strings not parallel to the diameter of "contraction" would meet the said condition as to the distance of the points of attachment, and that certain strings crossing and at an angle to the longest diameter, and connecting points within a limited arc from the ends of the 105 longest diameter would meet the said condition. If however the whole face of the

racket were strung with strings parallel to such strings, some of the strings would for a certain area of the blade remote from the centre, and to a greater extent the more remote from the centre, fail to comply with the said condition.

The strings can be arranged to attain the said condition for all practical purposes, by departing from the parallel relationship of 10 the strings of each set, and arranging them to an extent fan-wise, the degree of divergence from the parallel depending very much on the shape of rim adopted, the nature of the distortion permitted, and the magnitude of 15 the inclination of the main body of strings to the diameter of "contraction."

The degree of divergence need not be constant throughout the stringing and can even reverse in direction from side to side of the 20 set of strings.

The method of ascertaining the points of attachment of each string is shown by reference to the accompanying drawings in which,

Fig. 1 is a plan view of a racket embodying my invention and Fig. 2 is a diagrammatic view illustrating the mode and effect of stringing the racket.

a is the handle, *b* is the inside edge of the frame in what may be called its "normal" 30 position. *c* is the position of the same edge after it has undergone distortion.

The lines marked *d* join points on line *b* to the new positions of such points, when the racket frame is distorted to the position *c*.

35 The drawing of these two positions having been obtained a position for each string is found with a divider or other convenient measuring instrument, such that its two extremities are either closer together when the frame is in position *c*, than when it is in position *b*, or remain the same distance apart in the two positions. In the diagram shown it will be found by measurement that all the strings correspond to the above condition.

40 The positions shown are not the only ones which the several strings could occupy. It will be realized that given the lower end *f* of a string, *e. f.* as fixed, the upper end could lie anywhere in a certain zone without failing 50 to comply with the condition. For example, considering string *e. f.* in the diagram as one of a set which have to cross a corresponding set from the other side if the end *f* be fixed the position of the end *e* can be anywhere 55 between the points *x* and *y* without violating the condition; further as the point *e* approaches the point *y* the change in the length of the line *e. f.* produced by a given amount of distortion gradually decreases, until the 60 critical position *y* is reached in which the diminution in the length of *e. f.* is zero and beyond this it changes to an increase. The more nearly *e* approaches this critical position the greater force will have to be applied 65 at right angles to the string to produce a

given amount of distortion. If similar principles be applied in choosing the position of every such string a combination may be made in which the strings severally approach as nearly as is desired to the critical position 70 which exists for each one, as just described in the case of *e. f.* Thus the method of stringing in combination with a rim pliable in the plane of the rim can produce the desired resiliency of the racket.

75 The racket rim in its normal position, i. e. after stringing, may or may not be in a state of strain due to a preliminary distortion maintained by the initial tension of the strings.

80 In some cases it may be in order to attain a predetermined resiliency in the racket to place certain strings in violation to the said condition thereby opposing and to a degree limiting distortion, without inhibiting it 85 altogether. It may be observed that in some instances certain of the strings will be under less strain than others, owing to the fact that their relation to the rim is such that while one end remains fixed the other end will respond to the impact of a ball against the racket by a slight movement in the arc of a circle. This may happen especially with short 90 strings located near the handle of the racket, but this movement does not affect the action 95 of the racket.

95 What I claim is:—

1. A games racket characterized in that the rim is resiliently pliable in the plane of the racket, to afford the required resiliency when 100 the blade is struck by a ball, and the stringing is arranged not to oppose the yielding of the rim to attain such resiliency, the required resiliency being afforded wholly by the resilient pliability of the rim, the strings being 105 of comparatively non-stretchable material.

2. A games racket characterized in that the rim is resiliently pliable, and the strings are stretched between such points that on a contraction of one or more predetermined diameters and consequential extension of one or 110 more other diameters, the distances between the points of attachment of each string are not increased.

3. A games racket characterized in that 115 the rim is resiliently pliable in the plane of the racket and the majority of the strings are stretched between such points that on a contraction of one or more diameters of the rim, the result of a blow on the blade as of a ball 120 and consequential extension on one or more other diameters the distances between the points of attachments of each such string are not more distant, while one or more of the remaining strings are arranged to oppose the 125 distortion of the rim.

4. As a process in the making of a racket in which the rim is resiliently pliable in the plane of the blade, and the stringing does not 130 oppose the required resiliency of the racket

from being obtained from distortion of the rim, ascertaining the points of attachment of some or all of the strings by distorting a rim by means of pressure along a diameter, making a drawing in which the rim under normal tension, and the rim as so distorted are superimposed, determining therefrom the points of attachment so that in reference to some

or all of the strings the points of attachment are not more distant when the rim is distorted ¹⁰ than when in normal position and stringing the rim accordingly.

In witness whereof I have signed this specification.

CLAUDE ALBERT CLAREMONT.
